APPARATUS FOR CHANGING THE PITCH ANGLE OF REVERSIBLE-BLADE SCREW PROPELLERS

Application filed November 9, 1931. Serial No. 573,868.

The invention hereinafter to be described relates, in general terms, to propelling machinery for various kinds of water craft, and deals more particularly with certain improvements in the mechanism employed to change the pitch angle of reversible-blade screw propellers.

A water craft in which the motive power is a steam engine is usually equipped with a solid propeller, or one in which the blades are cast integral with the propeller hub. In most cases this is quite satisfactory on account of the fact that the steam engine is not only reversible with respect to the direction of rotation of its shaft but is also susceptible of being driven at greatly varying speeds of rotation.

The modern trend, however, is away from steam and toward the use of gas or internal combustion engines and these being generally irreversible power agents and more economically and efficiently operated at a constant or uniform speed of rotation it becomes necessary to provide certain apparatus by means of which the driving effort of the propeller may be made variable so as to move the vessel at different speeds, and also to supply means to apply this driving effort in opposite directions in order that the craft may be moved either in a forward or backward direction.

Reversing and speed reducing gear sets are sometimes employed to accomplish the above objects, although in certain respects they lack the essential requirements which are embodied in other blade-reversing mechanisms, and which are of great advantage when operating with prime movers such as the Diesel type of internal combustion engines.

Furthermore, many vessels, as for instance, yachts, fishing smacks and certain types of cargo carriers, which normally are propelled by sails, are equipped with auxiliary power, and a solid propeller in these instances becomes a drag, and necessarily greatly reduces the speed of the craft when operating wholly by wind power.

In the present invention I employ a differential gear mechanism which is power driven from the main shaft of the engine and which

can be made to actuate a feed screw for the purpose of changing the pitch angle of the blades of the propeller while the engine is operating at full or normal speed.

By applying a brake to either one, singly, of two geared brake drums the feed screw is set in motion and moved longitudinally of the shaft and the blades turned on their axes in a direction determined by which of the two drums is restricted in its rotary movement. Upon releasing the brake the blades remain in a positively secured and predetermined angular position.

An automatic feed stop arrangement prevents further axial rotation of the blades when either extreme of pitch angle, forwardly or backwardly, is reached, and an indicator shows the particular pitch angle or lead at which the blades are disposed at the time.

Facilities are also provided for correcting the pitch of each individual blade, and this is a feature which is of superior advantage in the manner of attaining and preserving correct balance of the propeller wheel.

The character of the invention may best be understood by reference to the description found in the following specification when taken in connection with the accompanying drawings in which is disclosed an embodiment thereof which, at the present time, I consider preferable to other possible forms in which the invention might be carried out.

In the drawings—

Fig. 1 is a sectional plan view of my apparatus;

Fig. 2 is an end view of the propeller hub, the cap being removed to show the link block;

Fig. 3 is a section on line 3—3, Fig. 1.

Fig. 4 is a composite view, in perspective, showing the foot of the blade and the split collar which secures it to the propeller hub;

Fig. 5 is a diagrammatical view showing the method of connecting the link block to the blade;

Fig. 6 shows, on an enlarged scale, the eccentric pin which is employed to locate the link in various positions on the link block;

Fig. 7 is an end view of a propeller blade shown in full lines to represent neutral or

feathering position, and in dotted lines for "ahead" and "astern" positions, respectively;

Fig. 8 shows an alternate method of securing the two parts of the housing together;

Fig. 9 is a full plan view of the apparatus, the propeller not being shown;

Fig. 10 is a side view of one of the brake bands;

Fig. 11 is a detail view of the automatic stop mechanism;

Fig. 12 shows the cammed face of the brake band ear;

Fig. 13 is a perspective view of the slotted sleeve-actuating lever for the automatic stop mechanism;

Fig. 14 illustrates the position of the indicating elements when the blades have moved to one extreme outward position of pitch angle;

Fig. 15 is a section on line 15-15, Fig. 9, and

Fig. 16 is a perspective view of the indicator end of the feed screw.

Similar reference characters are employed to identify like parts in all the different views of the drawings.

Referring to the drawings, and particularly to Fig. 1, it will be observed that the principal working parts of the mechanism are enclosed in a longitudinally and centrally split housing consisting of two similar structures, 1 and 2, which, when the apparatus is in operation is partially filled with a proper lubricant.

On each end of the housing proper are extended split hubs 1a and 2a and 1b and 2b, respectively, and through the hubs is a bore 3 a portion of which, at 3a, is made square in cross section.

On the extreme inner ends of the hubs 1a and 2a are semi-circular flanges 4a and 4b which are secured to the solid circular flange coupling 5 fixed on the main engine shaft 6.

Operating in the bore 3 is a feed screw 7, on the outer end of which is fixed the feed rod 8 extending through the bore 9 in the propeller shaft 10 to the link block 11, which latter is slidably mounted in the hub 12 of the propeller.

Disposed between the bosses 13, 13, is a bevel gear 14 which is screw threaded in its bore and operates on the feed screw 7. Meshing with and disposed on opposite sides of the gear 14 are two smaller bevel gears 15, 15, which are fixed, respectively, on shafts 16, 16 which are journaled in bearings 17, 17.

These shafts diverge, relatively, toward the forward end of the housing and on one end of each is fixed a gear 18, these two gears

(18) meshing with and located on opposite sides of the external gear 19 which is secured to the brake drum 20. On the inner ends, respectively, of the shafts 16 are gears 21, these

meshing with the internal gear 22 which is secured to the brake drum 23.

Operating, respectively, on the brake drums 20 and 23 are brake bands 24, 24, a side view of one of which is shown in Fig. 10. On the face of the band projects an ear 25 fixed on a supporting standard 26, and on the open ends of the band are other ears 27 on one of which is a cammed face (see Fig. 12) adapted to engage the reversely cammed surface of the brake arm 28. A bolt 29 passes through both the ears 27 and the cammed brake arm operates between the head of the bolt and the cammed ear so as to effect, when the arm is swung in one direction, a closing together of the brake band ends and tightly bind the band to the drum. An upstanding lever 30 is employed to actuate the brake arm.

To secure the two halves of the housing together I employ rings 31 and 32 having screw threaded engagement with correspondingly threaded portions 33 and 34, respectively, on the ends of the housing members.

In Fig. 8 is shown a modification in the method of securing the two members of the housing together, bolts 35 being employed in this instance.

The propeller blade 36 is axially rotatable in a split collar 37 which surrounds the shank or reduced portion of the foot of the blade, 38, and is screw threaded on its periphery into the opening 39 in the hub 12. A set screw 40 prevent rotation of the collar and a cap 41, threaded to the end of the hub, at 42, seats on the shoulder 43 and prevents backing out of the screws 40.

It will be observed that the link block 11 is provided with a guide rod 44 which passes through the end of the cap. This prevents any pumping action which might occur was the hole not carried completely through the cap.

To hold the link block 11, which preferably is made triangular in cross section, against rotation in the hub 12 I provide indents 45 in which the apices of the block seat and in which they may longitudinally slide.

On the inner face of each blade, at the foot end, is a crank pin 46 and on each face of the link block is an eccentrically mounted pin 47. Operable over and connecting with both of these pins is a link 48.

Referring to Figs. 5 and 7 it will be seen how longitudinal movement of the link block rotates the propeller blade. The small circle α represents the axis of the blade and around this central point swings the pin 46 on the blade. When the pin 46 is positioned on the radial line a the blade is set at extreme working pitch "ahead", and when on radial line b it is on extreme working pitch "astern". When it is desired to "feather" the blades—fore and aft—the pin 46 is moved to radial line c , in which position the link rests on the stop pin 49. The eccentric pin 47 moves lon-

gitudinally, backwardly and forwardly with the link block, in exactly the same manner as would the wrist-pin in a crosshead of a steam engine; and to complete the analogy, the link 58 serves in the same capacity as does the connecting-rod of the engine.

Due to possible inaccuracies in locating the pins or to slight dissimilarities in the pitch of the blades when molding or finishing I 10 have found that it is quite essential that means be provided to bring all the blades to a uniform pitch angle after assembling them on the propeller hub.

To accomplish this object I make the pin 15 47 eccentric (see Fig. 6) and by slightly turning it in its position in the block it has the effect of re-positioning the link—as shown in dot and dash lines—with a consequent change in the angularity of the blade in its position 20 on the hub of the propeller.

The actuation of the brake arms 28 to effect different changes in pitch angles of the blades is a manual operation performed by the engineer or other attendant in charge and 25 he is supposed to release the brake drums and stop the feeding of the feed screw when the desired pitch angle has been reached—as visually disclosed by the indicator. But in careless operating he might neglect to throw 30 off the brake at the proper time with the result that damage might be done to the parts. For this reason I consider it quite essential that the automatic stop-feed mechanism be incorporated in the structure of the apparatus.

In Fig. 14 the feed stop arm 50 is shown contacting with the collar 51 at a point indicated by the pointer as being the extreme pitch of the blade when working "astern".

40 Regardless of whether the engineer retains his grip on the brake lever after reaching the extreme working pitch point, or not, the automatic safety knock-off will act to release the brake at the proper time.

45 In operating the "ahead" brake drum the automatic knock-off or feed stop arm 50 will act on the collar only when the pin 46 has reached a position coincident with the radial line *c* (Fig. 5) or at a point at which 50 the blades are feathering; but unless the vessel is supplied with a large surplus of power it would be extremely difficult to operate the propeller with the blades standing fore and aft as their flat faces would be presented to the 55 water. In cases of emergency the collar 52 would act, however.

When the propeller shaft is not rotating and it is desired to change the pitch of the blades—as for instance, in a sail equipped 60 vessel and it is desired to feather the blades, fore and aft—I provide means whereby this may be accomplished manually. In the periphery of the drum 20 are a plurality of holes 20a and by inserting a round bar in 65 any one of them the drum may be rotated

and the chain of gears set in motion to move the screw 7 in either direction.

The automatic stop parts are shown in neutral position in Figs. 1 and 9. In Fig. 11 the screw 7 has been moved toward the 70 propeller, the "astern" brake band having been tightened, causing the slotted lever 53 to swing and move the grooved sleeve 54 forwardly and the feed stop arm 50 into the 75 position shown in Fig. 14.

By reference to Fig. 15 it will be noted that there are two of the slotted levers 53, one operating in a depression 55 in the housing part 1a and another in a like depression in the housing part 2a. This prevents cramping 80 of the sleeve as it moves over the housing hubs.

The numerals 0, 10, 20 etc. disposed in an arc on the indicator boards B may represent either pitch angles or leads in inches of the screw shaped blade; they are of considerable advantage to the engineer in correctly manipulating the friction bands in order to bring the blades to some predetermined position.

90 The coupling 56 joins the housing parts, 1 and 2, to the propeller shaft 10, keys 57 and set screws 58 being employed to secure the parts together.

It will be observed by reference to Fig. 95 3 that the screw member 7 is made square adjacent the portion 3a of the bore. This is to prevent turning of the screw when the gear 14 is rotating thereon.

When the blades are set to any desired 100 pitch and the vessel equipped with the device is underway, the housing parts 1 and 2 and the drums 20 and 23 rotate with the propeller shaft at engine speed, but the bands 24, of course, never revolve.

105 Let us assume, first, that the engine rotates "right hand", that is, according to the direction indicated by the arrow on the shaft coupling, shown in Fig. 9; also let it be understood that in this instance the "astern" brake band has been tightened, as shown in dotted lines Fig. 9. Now, the engine being operated, all parts of the apparatus supported 110 on the main shaft line, except the two brake bands, the brake drum 23 and the gear 22, 115 are revolving.

But, while the gears 21 rotate bodily with and around the axis of the housing parts, they also rotate on their own axes, due to 120 their engagement with the gear 22 which for the time being is stationary as it is fixed on the drum 23, which is being held rigid by the band.

The shafts 16 thus rotate at this time in 125 their respective bearings and on their own axes, and the gears 15 being fixed on these shafts and also in engagement with the gear 14, impart rotary movement to the latter which acts as would an ordinary nut turning 130

on the feed screw 7, the latter rotating with but not in the housing parts.

There is, therefore, a longitudinal movement given the screw 7 which is communicated by means of the feed rod 8 to the link block 11, and through the instrumentality of the links 48 interconnecting the pins 46 and 47 in the manner hereinbefore set forth, a rotary movement of the blades is finally accomplished, turning them in the present instance so that they lie in coincidence with the line *b*—*b*, Fig. 7—which represents the blade when in left hand pitch, the line *a*—*a*, Fig. 7 corresponding to right hand pitch angle.

The counter-rod 57 supporting the collars 51, 51a and 52 may be supported in suitable bearings (not shown), the yoked ends of the brake arms straddling the rod and engaging the collars when the brakes are being operated.

The embodiment herein described is, of course, primarily illustrative and my invention is, obviously, capable of interpretation in a wide variety of structures.

What I claim is:

1. In apparatus of the class described adapted for use on shafts for screw propellers having detachable blades, comprising a housing secured to and revolute with said propeller shaft, a feed screw in said housing extending through a bore in said propeller shaft to said propeller, a gear having a threaded bore mounted on said feed screw, a drum revolute on said housing, a gear fixed to said drum, a shaft, the axis of which is inclined from the axis of said propeller shaft, journaled in said housing, two gears fixedly mounted on said inclined shaft adapted to engage, respectively, the two first mentioned gears, and means whereby, when said propeller shaft and said housing are revolving, said drum may be held against rotation, causing a differential gear action to be had between the respective gears, the first gear mentioned rotating on said feed screw and moving it longitudinally in one direction in the bore of said propeller shaft.

2. In apparatus of the class described adapted for use in connection with the operation of changing the pitch angle of the blades of a reversible screw propeller mounted on a hollow shaft, comprising a housing mounted on said shaft and having a central bore therein, a feed screw operable in said central bore, a gear, having a screw-threaded bore, mounted on said feed screw and held against longitudinal movement in said housing, a differential gear set in said housing operable to rotate said feed screw gear on said feed screw in two directions while said housing is revolving in but one direction, a feed-rod connecting with said feed screw and extending through said hollow shaft to the interior of the hub of said propeller, a link block fixed on the outer end

of said feed rod and having faces the number of which correspond to the number of blades in said propeller, an eccentrically mounted pin on each face of said link block, a crank-pin on the inner end of each of said blades, and a link interconnecting the two said pins, said eccentrically mounted pin providing means to re-locate said link on and longitudinally of said link block whereby adjustments may be made to bring all of said blades into uniformity with respect to their pitch angles.

3. In apparatus of the class described adapted for use on hollow shafts for screw propellers having reversible blades comprising a centrally and longitudinally split housing, means to secure the two halves of said housing together, a central bore through said housing, a feed screw operable in said bore and having a portion extending to and into the hub of said propeller, a gear having a threaded bore mounted on said feed screw,

two brake drums revolubly mounted, respectively, on the two ends of said housing, a gear fixed on each of said brake drums, interiorly of said housing, two shafts journaled in said housing on opposite sides, respectively, of said feed screw, their axes being inclined from the axis of said screw, three gears fixedly mounted on each of said inclined shafts, one on each end and the third intermediate the length of the shaft, one end gear adapted to engage, externally, one of the brake drum gears and the other end gear meshing, internally, with the gear on the oppositely disposed brake drum, with the intermediate gear on each of said inclined shafts meshing with the said feed screw gear, a brake band on each of said brake drums, means to tighten, singly, either of said brake bands and hold the drum on which it is mounted against rotation while said housing is revolving, a link block on the end of said feed screw extension, and means to connect said link block with each of the blades of said propeller whereby they may be rotated, axially, in their mountings on the hub of said propeller.

4. In apparatus of the class described adapted for use on hollow shafts for screw propellers having reversible blades comprising a housing mounted on said shaft, a differential gear set in said housing, a feed screw axially mounted in said housing and adaptable of longitudinal movement, only, therein, a drum revolute on each end of said housing, a brake band on each of said drums, a brake arm on each of said bands adapted when swung in one direction to cause said band to become tightened on and hold said drum against rotation while said housing is revolving, the stopping of rotation of one drum acting, in association with said gear set, to move said feed screw in one direction, and by the stoppage of the other drum to reverse the movement of said feed screw longitudinally, and a pivotally mounted feed-stop arm one

end of which is actuated by said feed screw and the other end operable to automatically release the brake band on the operating drum whereby the longitudinal movement of said

5 screw ceases.

5. In apparatus for changing the pitch angle of reversible blade screw propellers comprising a hollow shaft on one end of which a propeller is mounted, a housing secured to the
10 opposite end of said hollow shaft, a feed screw traversing said housing and said hollow shaft, interiorly of both, a feed gear, having a screw-threaded bore, operable on said feed screw, means to hold said feed screw
15 against longitudinal movement in said housing, a brake drum revolvable on each end of said housing, braking means applicable to hold said drums, singly, against rotation on said housing, a differential gear set inter-
20 connecting and associated with both of said drums and said feed gear and arranged within said housing in such a manner that, when said housing is revolving, stoppage of rotation of said drums alternately will rotate said
25 feed gear, respectively, in two directions, with a consequent and corresponding longitudinal movement of said feed screw, and means cooperating with said feed screw to release the brake on either of said drums after
30 said feed screw has moved longitudinally in said housing a predetermined distance in either direction.

In testimony whereof I affix my signature.
MILTON D. THOMPSON.
